(57) **CLAIM**

The ornamental design for a wide chest belt with fastener for baby carrier, as shown and described.

DESCRIPTION

FIG. 1 is a front perspective view of an embodiment of the wide chest belt with fastener for baby carrier in a fastened state showing my new design;

FIG. 2 is a front view of the embodiment of FIG. 1;
FIG. 3 is a front view of the wide chest belt with fastener for baby carrier in a different fastened position

FIG. 4 is a right side view of the embodiment of FIG. 1;
FIG. 5 is a left side view of the embodiment of FIG. 1;

FIG. 6 is a top view of the embodiment of FIG. 1, the bottom view being a mirror image thereof; and,

FIG. 7 is a front perspective view in an unfastened position. The broken lines showing a baby carrier are for the purposes of illustrating environment and form no part of the claimed design.
